OIL PUMPING APPARATUS

Bengt Olsson, New York, N. Y., assignor to W. Hastings Swenarton, Montclair, N. J.

Application October 18, 1935, Serial No. 45,614

7 Claims. (Cl. 103—5)

My invention relates to a method and apparatus for the pumping of heavy oils and sludges. These sludges are usually extremely viscous and stable water emulsions and resist all attempts of pumping by ordinary pumping methods.

5 My invention especially relates to pumping such sludges that accumulate in the double bottoms of oil burning vessels.

It is to be noted that the invention provides 10 for a cold suction intake hose, which may be conveniently handled and led into the different pockets of the honey combed, double bottom structure of the vessel. Also as air is continuously withdrawn from the different portions of the 15 double bottom, the highly explosive gases which are generated therein by the oil residues are most effectively removed during the pumping, and the tank is left in a gas free condition when the pumping is finished, and all danger of explosion 20 is removed when welding, riveting or other "hot work" repairs are afterwards undertaken.

I have found that air sucked into the suction line by a moderate vacuum created by a steam 25 jet pump placed at the discharge end of intake suction line, will cause the material to travel through the suction line in form of a wave or solid slug which seals the suction line during its travel therethrough.

As my invention relates to a certain grouping 30 together of known elements, and as I by this novel combination attain new and useful results, I therefore also claim as a method the several co-operating steps required for performing my improved pumping operation.

35 In the drawing

Figure 1 is a diagrammatic, fragmentary, longitudinal section of an oil burning vessel showing a preferred form of apparatus removing viscous sludge from the double bottom thereof and discharging it through a convenient pipe line, all 40 in accordance with my invention;

Figs. 2 and 3 are respectively a detail fragmentary plan view and elevation of such apparatus; and

45 Fig. 4 is a fragmentary elevation of a modification.

In the drawing where like reference characters designate corresponding parts; 1 denotes the ship from which the viscous sludge 2 in the compartments of the double bottom 3 is removed. The suction line 4, preferably a 4 inch flexible bronze hose is led into any desired pocket of the double bottom through the conventional manholes and lightening openings.

55 At the end of the hose 4 is attached the re-

ducing nipple 5 and the other end is screwed into the suction end of the steam jet pump 6, which discharges into the relief trap 8 through the short nipple 7, with which the relief trap is provided. The trap also has a connection 9, through which the material is transferred into the bilge line 10.

The active portion of the bilge line 10 is preferably cut off from the rest of the line by means of a valve 11. From the bilge line 10, the ballast 10 pump 12 sucks the material and discharges it through a conventional pipe line 13 into a convenient storage space, either inside or outside the vessel.

The trap 8 is also provided with a valve-controlled line 14 through which the major part of the steam escapes thus preventing an excessive back pressure on the steam jet pump 6, which feature is essential as otherwise pumping will cease entirely. The steam necessary for the operation of the jet pump is furnished through the high pressure steam line 15 which is equipped with a customary valve 16.

The intake nipple 5 is preferably provided with crossbars 18 in order to prevent rags, sticks, etc. 25 from entering the transmission line and interrupt the pumping.

The operation preferred in carrying out my improved pumping method in the above described improvement is as follows:

The steam valve 16 is opened and the ballast 30 pump 12 is started. The high pressure steam, which escapes in the direction of flow through the nozzle of the jet pump will expand and as the expansion takes place a considerable amount 35 of the steam will condense and a vacuum forms in the steam jet which travels at a very high velocity. Into this travelling vacuum air will be sucked in and an air stream becomes established through the suction hose 4.

The intake nipple 5 is then dipped into the viscous material 2, care being taken that the intake is not completely submerged so that atmospheric air may freely enter the suction line together with the material, which then, upon entrance in 45 the line forms a slug sealing the line. This slug is now pulled by the low vacuum, about 12 inches of mercury, which will have been established in the line 4 by the action of the steam jet as aforesaid, and such slug will be discharged through 50 the terminal orifice of the nipple into the trap 8 and in a direction substantially tangential to the cylindrical wall of said trap. It is to be noted that when the slug passes into and through the steam jet of the pump it is blown into fragments 55

5 forming a rapidly moving spray which contacts with the trap wall and in violently sweeping along the side walls of the trap become separated or de-emulsified into water and oil which readily settle in the trap as they come to rest therein.

10 From the relief trap the major portion of the steam and air introduced into the trap escapes through the relief line 14 and an excessive back pressure is thus prevented in the trap 8. I have found that when the valve 17 is so throttled down, with respect to the capacity of trap 8 and the capacity and pumping rate of pump 12, that about a pressure of two to three pounds per square inch exists in the trap, a low and substantially continuous vacuum of about 12 inches as aforesaid can be maintained in the suction line 4 during the passage of the sludge from the nozzle to the steam jet and this vacuum is only broken during the short interval of the passage of 20 the sludge through the jet.

25 From the steam relief trap 8 where the discharged slug spray is collected, the ballast pump 12 sucks the material through the connection 9 and bilge line 10 and the pump suction is assisted by the trap pressure so that proper priming of the ballast pump is at all times maintained. Inasmuch as the viscous emulsion has been effectively broken down and only a mechanical mixture of hot air and water collects in the trap, the 30 draining of the trap does not prevent any problem and the ballast pump which usually is of the reciprocating type is able to deliver the pumped material to a considerable distance and elevation.

35 In this connection it is to be noted that any force pump can be used for the trap discharge; a centrifugal pump or even a steam jet pump provided with a check valve at its intake end will satisfactorily serve for this purpose.

40 The rapidly intermittent slug formation during the pumping operation is of the utmost importance insofar as the efficiency of the operation is concerned as thereby much greater quantities of sludge, some 200% to 400% can be pumped in a given time interval than is possible by a method 45 wherein the slug is emulsified with air and broken up in fine particles in air suspension and in which condition they are transported through the discharge line to an overside delivery receptacle, such as a slop barge as commonly employed for 50 this purpose.

55 It is of the utmost importance that the point of introduction of the steam into the line 4 be remote from the nozzle 5 and it must be in close proximity to the steam relief trap 8, preferably a couple of feet therefrom, as otherwise were the steam connection at the nozzle, or say within a foot or two therefrom, it would not be possible to introduce air at the nozzle and consequently the beneficial gas-freeing by such air suction into 60 the line during pumping operation would not be realized. Furthermore, by connecting the steam jet pump into the line 4 in close proximity to the trap, the nozzle 5 and hose 4 can be conveniently introduced into any double bottom pocket of any 65 size, however small, through the lightening holes of the bottom frames, and when so introduced can be conveniently manipulated by the operator due to the small size of the intake nozzle member which can be employed and especially also because the steam being introduced remote from the nozzle does not heat up the same to render the handling objectionable.

70 Another very essential and important feature of my invention resides in the fact that the operators are not subjected to any possibility of being

scalded by a back-firing through the nozzle 5 of the steam introduced into the line, since such steam, due to the unobstructed passage afforded into the trap 8, will always flow forwardly into the trap from which it can freely escape through the vent pipe 14. Also as the slender and relatively delicate steam hose 15 is always outside the double bottom wherein the operators are stationed, they are not subjected to any risk of being scalded or fatally injured should such steam hose 10 burst.

15 All of these advantages are realized without the employment of any check valve in line 4 and which check valve is objectionable because it tends to restrict the free flow of the slug there-through and also promotes the tendency for such line to become clogged by sticks or other foreign matter.

20 While this invention has been described with special reference to the removal of sludge from the double bottom of ships for which purpose it is admirably adapted for the reasons hereinbefore stated, this invention is likewise unusually applicable for the removal of sludge from the storage tanks, especially those on oil tank-farms 25 and refineries where voluminous deposits of rust scale mixed with oil sludge frequently occur. Such scale I have found is completely pulverized by the high velocity steam jet coupled with the aforesaid violent de-emulsifying action to which 30 it is subjected in the trap.

25 It is to be noted that the material discharged through the high pressure steam jet is heated to near the atmospheric boiling temperature of water or say 200° F. Now, therefore, the material 35 being a mechanical mixture of oil and water, the pump suction, unassisted, could not pull it into the force pump inasmuch as the highly heated water turns into steam the moment its temperature is higher than that at which water boils 40 when subjected to the vacuum created by the pump suction.

30 The most essential phase of my method is therefore the creation of a super-atmospheric pressure or so-called positive pressure in the relief trap, because even a slight pressure will be 45 sufficient to prevent any boiling i. e. considerable steam generating in the trap.

35 As a steam jet pump will readily create the low 50 vacuum necessary for the slug transmission through the suction line when discharging against a low pressure and at the same time the desideratum of a pressure delivery to the pump of the heated material is accomplished, the consequent successful handling by a force pump, either of the mechanical or steam jet type, of aforesaid viscous material is assured.

40 In this connection it is also to be seen that the connection 9 is so positioned in the trap 8, that the full centrifugal force of the deflected high 45 velocity spray will assist delivery to the force pump.

45 I have described my preferred apparatus as having a single suction intake hose to the trap, but it is readily seen that two or even more separate suction lines may be connected to a relatively small trap as the pumping rate of the force pump determines the number of intake hoses employed.

50 Referring to the drawing, it is to be noted that the vent line 14 is provided with a control valve 17, the pressure of which eliminates a close proportioning of the vent line.

55 In the modification shown in Fig. 4, the discharge from the trap 8 comprises a connection 60

20, equipped with a swing check-valve 21, to a steam jet pump 22, which latter discharges the pumped material through the discharge line 24. The jet pump 22 is provided with the high pressure steam inlet 23 through which the operating steam enters the jet pump. Such a construction functions generally similar to that shown in Fig. 1 wherein a reciprocating pump is employed and makes it possible for a steam jet pump to handle the hot pumped material from trap 8 inasmuch as the steam vent 14 prevents an excessive amount of steam to enter the discharge line 23, while the slight pressure maintained in trap 8 insures the priming of the steam jet pump at all times during the period of discharge of the pumped material from the trap 8.

I do not wish to be understood as limiting myself to the specific details of construction as it is manifest that variations and modifications may be made in the adoption of the device to various conditions without departing from the spirit and scope of my invention.

Having thus described my invention, what I claim and desire to obtain by United States Letters Patent is:

25 1. The method of pumping viscous material which comprises introducing a high pressure steam jet into a transmission line, effecting the sucking into the steam jet of the material to be pumped, blowing said material into fragments by the force of said jet, separating the steam from the pumped material, allowing steam to escape from the transmission line at a point close to the steam jet, restricting such steam escape so as to retain low pressure steam in the transmission line to thereby assist in delivering the pumped material to a force pump and to substantially prime the pump during the period of said delivery.

40 2. In a pumping apparatus for viscous material, a suction transmission line, a steam jet at the discharge end thereof, a chamber in communication with said transmission line and adapted to contain steam and pumped material, a vent line from said chamber, means for draining the chamber and a control valve in the aforesaid vent line.

45 3. In a pumping apparatus for viscous material, a suction transmission line, a steam jet at the discharge end thereof, a chamber in communication with said transmission line and adapted to contain steam and pumped material, means for draining the chamber and means for restricting the steam escape therefrom and to maintain a super atmospheric pressure in said chamber.

50 4. The method of pumping viscous material which comprises introducing a high pressure steam jet into a transmission line, effecting the sucking into the steam jet of such material to be pumped, blowing said material into a high velocity spray by the force of said jet, separating

the steam from the pumped material and then, while permitting the separated steam to escape from the transmission line, effecting the delivery of the pumped material to a force discharge-pump while utilizing the momentum of the high velocity spray to substantially assist in the priming of the pump during the period of said delivery.

5 5. A pumping system for removing viscous oily material together with the air and gases from a double bottom tank of a ship and over the 10 side thereof, comprising in combination a substantially prone suction hose adapted to be led into the double bottom tank from the tank top, a steam jet pump connected thereto, a separator pressure trap, a connection from the jet pump 15 to said trap, a vent line from said trap adapted to be projected over the ship's side, a force pump connected to said trap and a discharge line over the ship's side from said pump.

20 6. The method of pumping viscous material 20 through a transmission system, which comprises positioning an intake line in a substantially prone position, introducing a high velocity steam jet, projecting in the direction of the desired flow of such material through the system, into said intake 25 line at a point remote from the suction end thereof so as to create a partial vacuum in said line, admitting viscous material to be pumped into the suction end of said line together with sufficient air to impart a rapid movement to said 30 material as it enters the steam jet, blowing the pumped material into a high velocity spray by the combined action of said jet and said air, separating the air and steam from the pumped viscous material and causing the discharge of 35 the separated air and steam from the system while simultaneously forcing the pumped material separately out of said system.

7. The method of pumping viscous material 40 through a transmission system, which comprises introducing a suction line into contact with the material to be pumped, projecting a high velocity steam jet into said line in the direction of the desired flow of such material through the system and at a point remote from the suction end of said 45 line so as to create a partial vacuum therein, sucking viscous material to be pumped, together with sufficient air to impart rapid movement to said material, into the suction end of said line, blowing the pumped material so introduced into 50 the line into a high velocity spray composed of viscous material, steam and air, delivering such high velocity spray into a separation chamber, separating the viscous material of said spray from the associated steam and air, while simultaneously maintaining in such chamber a super-atmospheric pressure of several pounds per square inch to thereby facilitate the discharge of the pumped material from said chamber and separately removing the pumped material from said chamber. 55

BENGT OLSSON.
